UNITED STATES PATENT OFFICE

2,454,566

HEARSE

William H. Pfeiffer, Seattle, Wash.

Application June 11, 1945, Serial No. 598,715

12 Claims. (Cl. 214—83.24)

1

The hearse, in its functional or utilitarian aspect, must be adapted for loading or unloading to right or to left, rather than solely at the rear, for frequently it must draw alongside a curb. Caskets are always heavy, and may weigh as much as one thousand pounds, creating a real problem to pall-bearers in loading and unloading, the more so as their number is limited, and they are frequently not robust; the casket can only project partway so long as it is supported within or by the hearse; and an appearance of exertion in picking up or depositing the casket is deemed unseemly.

Side loading hearses have been known heretofore. In these the casket rests on or above the floor, and the floor is elevated, primarily because only thus can the casket be fittingly displayed. For unloading, the casket and its supporting bier table slide outwardly, and in so doing are rotated through 90°, to project the forward end laterally outwardly. Still, the casket is elevated as it was during transportation, and is difficult to lift or slide and carry endwise so elevated until the projecting end of the bier table is cleared, and then to lower to carrying position. Loading is even more difficult.

It is the primary aim of this invention to provide a hearse which is essentially side loading, which will support the casket in normal elevated transporting position, but which will permit lowering and outward swinging of the casket while still hearse-borne to a convenient carrying level and position for the pall-bearers on the sidewalk or street, and which in loading will receive the casket at the lower level, and thereafter, by power means, will elevate the casket, swing it into longitudinal transporting position, and close the side closure or window. Though shown and described as essentially side loading, it is obvious that the hearse may also have a rear door, and be operated as a rear-loading hearse if that be desired, though such operation may not utilize all the advantages of side loading.

Likewise it is an aim to provide mechanism suited to the power available, which will not detract from the appearance of the vehicle, which is quiet in operation, and which adequately meets all requirements, including those special requirements introduced by the novel arrangement of the principal elements, including, for example, means to counteract the unbalanced overhang or sag of the outwardly swung bier table, tending to slope it downwardly and outwardly.

Various mechanical aids have been incorporated in hearses, such as tracks to constrain the bier table to move into laterally projected position and to support the overhung weight when so projected; power means to effect such projection; and chassis-leveling devices to prevent the casket from rolling endwise off an otherwise inclined, outwardly projected bier table. All

2

such mechanical aids, including those introduced by this invention, must be thoroughly reliable in operation, so that no accident or failure interrupts the funeral ceremonies. They should also be quiet in operation. Electrical operation has been employed, as has hydraulic means, such as herein illustrated; the latter has some slight advantage in that it tends to be quieter, but otherwise either such means has been found acceptable. The use of any such means, at will, is to be considered as within the broader aspects of this invention.

In a somewhat more specific sense, among the objects of this invention are: provision of control means to effect successive operations in a predetermined sequence and relation to other operations; to provide controls located conveniently to the driver, which has the further advantage that the casket and driver may be separated by a limousine-style glass partition; to arrange selective controls, cooperating with a sequence control, to govern right or left loading, and to regulate the extent of lowering of the bier table in accordance with variations in level between the sidewalk and the street, or for other reasons, to provide automatically operable closures for the casket space, and for the notch into which the casket is lowered, which closures blend with or constitute elements in the exterior finish or decorative scheme of the hearse.

It will be clear, from the above, that the invention comprises a novel hearse, a novel arrangement of the several primary elements thereof, and a novel arrangement of a complete system for enabling the transporting and unloading, or loading, of a casket in a manner different from that possible with hearses of a construction now known. The invention also comprises certain novel elements of such a hearse. The nature and objects of the invention will appear more clearly as this description progresses, and from the claims.

The form of construction illustrated in the drawings is not necessarily, in its details, a preferred form, but serves to illustrate, without undue complications, the principles of the invention. Such details, then, may be changed without departing from the spirit of the invention. Its scope will appear as this description progresses, and should be limited only to the extent indicated by the claims.

Figure 1 is a side elevation with parts broken away, illustrating the hearse of this invention.

Figure 2 is a horizontal sectional view, substantially along the line 2—2 of Figure 1.

Figure 3 is a transverse vertical sectional view, substantially along the line 3—3 of Figure 1.

Figure 4 is a plan view of the bier table supporting and moving means, the view being taken substantially along the line 4—4 of Figure 5, and Figure 5 is a longitudinal vertical section through

the same mechanism, taken substantially along the line 5—5 of Figure 4.

Figure 6 is a diagram of a typical hydraulic system for accomplishing the several necessary operations. Figure 7 is a plan view of the head of the sequence valve employed in such a system, illustrating the sequence of operation.

Figure 8 is a development of the hollow cylindrical rotative valve core used in such a sequence valve, and Figure 9 is a corresponding development of the cooperating valve casing.

The hearse incorporates a chassis 9 supporting the body 90, with the glass partition 91 to divide the casket space 92 from the driver's space 93. The driver and his assistant occupy the seats 94. The body may have a rear door, though none is shown in the drawing, but in any event is provided with side openings at right and left, admitting to the casket space 92, each of which is closed by a window or similar closure 8 which is suitably movable between open and closed positions. For example, it is hinged at its top to swing upwardly and outwardly, as will be later explained.

The floor 95 of the space 92 normally lies at a level such that the casket, supported indirectly thereupon, lies above the level of the wheel wells or rear fenders 96, whereby the casket is supported in view through the windows 8. Adjacent its forward portion, however, the floor 95 is notched, as indicated at 97, to a materially lower level.

Supported within this notch is an elevator 3, which is guided for vertical movement by upright posts 30, supported from the chassis 9. Vertical movement of the elevator 3, and its leveling, is accomplished by means of four multiple extension jacks 31, supporting it from the chassis 9. It will be understood that the hydraulic jacks 31 constitute one means of raising and lowering the elevator, but that other equivalent means might be substituted therefor, according to the broader phases of the invention.

Pivoted upon the elevator 3 is a bier table 1. The pivot axis, indicated at 10, is adjacent the forward end of the bier table, so that the bier table projects materially rearwardly from the pivot point 10, as may best be seen in Figure 2. The bier table in a sense is a turn table, though not symmetrical, longitudinally, with respect to its axis of rotation. The bier table is provided with the usual devices to facilitate the handling and securing of the casket, as for instance the rollers 11 and the bier pins 12, and with suitable supporting bearings, not shown, between itself and the elevator 3.

Rotation of the bier table is accomplished by means such as a double-acting jack 13 which is supported from the elevator 3 and which is connected to the bier table 1 by such means as a rack 14, connected to move with the piston 15 of the table-turning jack, and meshing with a pinion 16 fast upon the shaft 10, which in turn is connected to the bier table, and which is journaled at 32 in the elevator 3. Again, as was the case with the lifting jack 31, the jack 13 and the associated table turning mechanism represents only a convenient mechanism for accomplishing this result, so far as concerns the broader phases of the invention.

In similar fashion, and as representative of various mechanism that might be used, the windows 8 are arranged to be opened and closed by double-acting jacks 81 with their pistons 82. Each window is hinged at 80, just within and above the margin of the side aperture which the

closure closes. The hinge mechanism 83 is such as to accomplish the desire degree of swinging of the closure, and the piston 82 is connected by suitable means, such as 84, to effect swinging of the closure. One set of jacks 81 is provided for the right window and a similar set for the left window. The windows might be opened by lengthwise accordion folding, or in any suitable manner.

The hydraulic system for accomplishing the several necessary operations in the proper sequence is illustrated diagrammatically in Figure 6. The sequence of operations is indicated by the end view of the sequence valve in Figure 7, and the valve itself and its cooperating valve casing are shown diagrammatically in the developments of Figures 8 and 9, respectively. The sequence valve is indicated generally by the numeral 2, and its casing by the numeral 20. The direction or side of the hearse toward which the operations occur is governed by the position of a right-or-left valve 4, and certain lowering operations are controlled by the valves 5R and 5L. The controls for these valves are located conveniently to the drivers.

Referring now to Figure 6, which shows the general diagram of the hydraulic system, and to Figures 7, 8, and 9 which illustrate details of the sequence valve, it may be seen that in general liquid is drawn from a reservoir 70 by way of a low pressure or suction line 71 to the low pressure side of pump 7, and is delivered by way of a pressure line 72 to the sequence valve 2, or if the fluid may not pass the valve 2, then the fluid is returned past the pressure-relief valve 73 and relief line 74 to the reservoir 70.

Disregarding for the moment the internal structure of the sequence valve 2, and referring simply to Figure 7 in conjunction with Figure 6, it may be seen that the pressure fluid enters the hollow interior of the rotatable valve core 2 of the sequence valve, which is normally in the locked position A. If, however, the valve is rotated in the direction of the arrow, shown in Figure 7, by means of the handle 21, it arrives at position B (a spring ball click or similar device, not shown, accurately locates the valve in such position). Communication is thereby established between the interior of the valve 2, by means of the conduit 39, the right-or-left valve 4, and one or the other of the conduits 38L and 38R, and the master cylinders 37, with the jacks 31 at the left or right sides of the hearse. The purpose of this is to insure that there is adequate pressure in all the jacks 3, and that the weight of the bier table and casket is supported by these jacks 31, rather than upon the floor 95.

The valve 2 is next rotated to position C. This retains the pressure fluid in the cylinders 31, and admits pressure fluid by way of the conduit 89, and right-or-left valve 4, and thence by way of the conduit 88R or 88L to the appropriate window jacks 81, and at the same time a low pressure connection from the opposite end of the corresponding jack is established by way of the lines 87L and 87R past the right-or-left valve 4, and thence by way of the conduit 86 and an exterior groove of the valve 2, to a relief conduit 75. The window swings open.

The valve 2 is next rotated to position D. This retains the jacks 31 and 81, previously connected with the pressure source, in their respective attained conditions, that is, with pressure admitted into the jacks 31 and with the closure 8 on the

proper side now swung open. It also admits pressure fluid from the interior of the valve 2, by way of the conduits 19R or 19L, and past the right-or-left valve 4, to one end or the other of the table rotating jack 13, by way of the conduits 18R and 18L. The opposite end of the same jack at the same time is vented by way of the paired set of conduits, and through exterior passages in the valve 2 to the relief conduit 76. This causes the bier table 1, which becomes then a turn-table, to rotate to the proper side through the closure which was just opened by the raising of the appropriate window. The bier table is now in the outswung position, shown by dash lines in Figure 2.

The valve 2 is next swung to position E, which locks all the jacks 31, 31, and 13 in their acquired status, and which causes the pressure fluid in the line 72 to take now the course 51L or 51R or both, to the extent that the valves 5L and 5R, respectively, may be opened. These valves are lowering valves and are normally closed. Their function is primarily to permit relief of pressure from the jacks 31, by way of the master cylinders 37 and lines 36R or 36L, either back to the reservoir by way of the lines 51L or 51R, or to the suction side of the pump by way of the lines 52R and 52L, respectively. By this means the fluid trapped in the jacks 31 may be bled out as slowly or as rapidly as may be desired to lower the elevator 3 to whatever level may be desired, and to maintain the outwardly swung bier table level while it is being lowered. To the latter end suction may be applied on the side opposite that toward which the bier table projects, if necessary, and by appropriate manipulation of the valves 5R and 5L. When the bier table has been lowered to the appropriate extent, it will be in a loading position such as is shown in Figure 3, and at this level the casket may readily be engaged and lifted slightly by the pall-bearers standing on the curb or sidewalk.

In loading from the position of Figure 3, after the casket has been placed on the outswung bier table the valve 2 is turned to position F, the valves 5L and 5R being in neutral position, and fluid is admitted past the valve 2 and by way of the conduit 39 and the two conduits 38R and 38L to the several jacks 31. Again these jacks can be controlled to whatever extent may be necessary to keep the bier table level, by the valves 5L and 5R. The jacks 31, incidentally, are vented at their upper ends to permit such raising, and hence require no return line.

When the bier table and casket have been elevated to a level somewhat above the floor 95, the valve 2 is turned to position G, which locks the jacks 31 in their raised position, and supplies or vents fluid, as the case may be, through the conduits 19L and 19R to effect inward swinging of the bier table into its longitudinal transporting position, as shown in Figure 1, or in the upper position of Figure 3. This, of course, is merely operation of the jack 13 reversely to that previously described.

When the bier table is swung in, the sequence valve is turned to position H. In this position the jacks 31 and 81 are locked in their attained condition, and now fluid is supplied by way of the conduit 86, valve 4, and conduits 87R and 87L to the jacks 81 to operate them the reverse of that previously described, and thereby to swing closed that closure 8 which formerly was opened. This having been accomplished, it is only necessary to complete the rotation of the valve 2 to

its initial position A, where all jacks are locked in their respective attained positions. The bier table may be lowered slightly in this position, to rest it more solidly upon the floor 95, by manipulation of the valves 5L and 5R while the valve 2 is in position A.

Incidentally, it may be seen in Figure 3 that accordion folds 98 are provided between the lateral edges of the elevator 3 and of the hearse body 90, which in the upper position of the elevator will close the notch 97 into which the elevator drops and which will blend with or form part of the decorative scheme of the hearse body, but which will automatically fold outwardly as the elevator is lowered. The closures 8 and any decorative molding about them, as viewed in Figure 1, also constitute part of the decorative scheme of the hearse body.

The right-or-left valve 4 is merely a valve core having lands and shiftable to the end of closing one port and opening a companion port of a pair, the ports and lands being so arranged as to accomplish operation of the jacks for right loading in one position, and the jacks for left loading in the other position. The valve is encased within a valve casing 40 and is provided with a handle 41 by which it may be turned. Its rotation acts through a pin 42 in a helical slot 43 to shift the valve longitudinally; a half turn will effect movement between one position or the other, whereby its handle 41 forms a convenient indicator as to which side is ready for loading or unloading operation. Any suitable construction to this end may be employed, in lieu of the construction shown.

It is believed that detailed study of the valve casing developments of Figures 8 and 9 is scarcely necessary. In the casing, Figure 9, the ports have been given the numeral corresponding to the conduit which leads from such port; the port 39 is divided and communicates at two points 180° spaced from one another by way of the ports 39a and 39b. Cooperating with this shell is the hollow valve core 2, in which all through ports have been given the same numeral as the casing ports of Figure 9 with which they cooperate, with this suffix letter c. The relief ports 89R, 86R, 19Lr, and 19Rr are not through ports, but inclined grooves or channels in the outer face of the valve core serving to effect relief of the port of corresponding number. The valve and casing will be seen to operate in the sequence and to the end explained above, if, for example, a tracing of either the casing or the shell is overlaid over and moved with respect to the other, in the sequence indicated by the several letters which correspond to the positions of Figure 7. Furthermore, it should be borne in mind that the valve itself is simply one means of accomplishing the end in view, in proper sequence, and that any other means capable of accomplishing this end may be employed. Even more, it should be remembered that the hydraulic system was chosen simply because it may be somewhat quieter in operation than an electric system, but that an electric system may be employed, if desired, in substitution for the hydraulic system, and such a modified system would still be within the broader aspects of my invention, as defined in the claims.

I claim as my invention:

1. A hearse comprising a bier table, means supporting the same for pivotal movement about a fixed vertical axis from an upraised lengthwise transporting position into an outwardly swung

position, and from such upraised to a lowered unloading position, and control means prohibiting lowering movement until completion of the outswinging movement, and reversely, prohibiting inswinging movement until completion of the raising movement.

2. A hearse comprising a bier table, means supporting the same for angular, generally horizontal movement from an upraised lengthwise transporting position to an outwardly swung position, and from such upraised to a lowered unloading position, but restraining the same from bodily lengthwise movement, and control means prohibiting lowering movement until completion of the outswinging movement, and reversely, prohibiting inswinging movement until completion of the raising movement.

3. A hearse comprising a bier table, a floor above which said bier table may be disposed in a lengthwise transporting position, and having a transverse notch of a width exceeding the width of the bier table, and means supporting and guiding the bier table for movement generally horizontally from said transporting position into an outwardly swung and lowered unloading position, wherein the bier table is between the edges of said notch and below the floor level, and for reverse movement.

4. A hearse comprising a bier table, a floor above which said bier table may be disposed in a lengthwise transporting position, and having a transverse notch of a width less than the length, but greater than the width, of the bier table, an elevator disposed in said notch, whereon the bier table is pivoted to swing horizontally, and means to swing the bier table from transporting position to an outwardly swung position, and to lower the elevator and outwardly swung bier table into the notch to an unloading position, and vice versa.

5. A hearse comprising a bier table, an enclosure about said bier table, including a floor above which said bier table may be disposed in a lengthwise transporting position, said floor having a transverse notch of a width less than the length, but greater than the width, of the bier table, a closure constituting a side of said enclosure, and movable between open and closed positions, an elevator disposed in the floor's notch, whereon the bier table is pivoted to swing horizontally through the side, when said closure is in open position, and means to move said closure to open position, to swing the bier table outwardly, and to lower the bier table into the notch to an unloading position, and vice versa.

6. A hearse comprising a bier table, an enclosure therefor, means supporting and guiding said bier table for outward swinging from a lengthwise enclosed transporting position into a projected position, a closure openable to permit such swinging, means to lower such outwardly swung bier table to an unloading position, and control means constraining energization of the preceding means to effect in sequence, first, opening of the closure, second, outward swinging of the bier table, and third, lowering of the bier table.

7. A hearse comprising a bier table, an enclosure therefor, having openable right and left closures, means supporting the bier table for angular movement between a lengthwise enclosed transporting position and either a right or left outwardly swung position, and for lowering to an unloading position, means constraining said preceding means to operation, in sequence, of a

closure to open, of the bier table, to swing outwardly, and finally to lower, and means to predetermine the side towards which such movement occurs.

5 8. A hearse comprising a bier table, means supporting and guiding the same for angular movement between a lengthwise transporting position and a position outwardly swung at one side, and then for movement into a lowered unloading position, means constraining said preceding means to movement of the bier table, in such sequence, and in the reverse sequence, and means to control the degree of lowering of the bier table.

10 9. A hearse comprising an elevator; a bier table pivoted by a vertical axis located near one end of the bier table, upon said elevator; lifting jacks operatively connected to raise and lower said elevator; a turning jack upon the elevator operatively connected to rotate said bier table from an elevated lengthwise transporting position to an outwardly swung position; and means to energize said jacks, in sequence, to effect outward swinging of the bier table and then lowering of the elevator and the outwardly swung bier table 20 into an unloading position, and, thereafter, reverse operation.

25 10. A hearse as in claim 9, wherein the jacks are hydraulically operated, and the jack-energizing means includes a sequence valve and a lowering valve.

30 11. A hearse comprising an enclosure having an openable side closure; an elevator within said enclosure; a bier table pivoted upon said elevator to swing about a vertical axis located near one end of the bier table; a jack operatively connected to open said closure; lifting jacks operatively connected to lower and raise said elevator; a turning jack upon the elevator operatively connected to rotate said bier table from an elevated lengthwise transporting position to an outwardly 35 swung position; governing means for energizing said jacks in the sequence indicated; and further means to control the extent of lowering of the elevator and outwardly swung bier table, into unloading position.

40 12. A hearse as in claim 11 wherein the bier table may swing to right or to left, and the enclosure has two openable closures, a right and a left, and including further reversible means to predetermine the energization of jacks for right or for left unloading or loading.
